E. I. DODDS,
FIRE BOX STAY BOLT FOR LOCOMOTIVE AND OTHER BOILERS,
APPLICATION FILED OCT. 13, 1911.

UNITED STATES PATENT OFFICE.

ETHAN I. DODDS, OF CENTRAL VALLEY, NEW YORK, ASSIGNOR TO KERNER MANUFACTURING COMPANY, OF PITTSBURGH, PENNSYLVANIA, A CORPORATION OF PENNSYLVANIA.

FIRE-BOX STAY-BOLT FOR LOCOMOTIVE AND OTHER BOILERS.

1,146,431.

Specification of Letters Patent.

Patented July 13, 1915.

Application filed October 12, 1911. Serial No. 654,509.

To all whom it may concern:

Be it known that I, ETHAN I. DODDS, a citizen of the United States, residing at Central Valley, in the county of Orange and State of New York, have invented certain new and useful Improvements in Fire-Box Stay-Bolts for Locomotive and other Boilers, of which the following is a full, clear, and exact description, reference being had to the accompanying drawings, forming part of this specification, in which—

Figure 1 is a side elevation of one form of bolt embodying my invention; Fig. 2 is a similar view of a bolt of the same general character as that shown in Fig. 1, with modified form of securing means; Fig. 3 is a sectional view on the line X—X of Figs. 1 and 2; Fig. 4 is a side elevation of another modified form of stay bolt; Fig. 5 is a sectional view on the line Y—Y of Fig. 4; Fig. 6 is a side elevation of another form of bolt; Fig. 7 is a sectional view on the line Z—Z of Fig. 6; Figs. 8 and 9 are views similar to Fig. 7, showing modified forms of bodies of the bolt in cross section; Fig. 10 is a side elevation of another form of bolt; and Fig. 11 is a sectional view on the line W—W of the ball end of the bolt shown in Fig. 10.

This invention relates to improvements in yielding stay bolts in which the main body of the bolt is adapted to yield or vibrate when the fire box or boiler sheets expand or contract.

The object of my invention is to provide a bolt of this character which is cheap of construction, which is readily placed in position, and which is adapted to yield in any direction to compensate for the movement of the fire box and boiler sheet, which are connected to each other by means of a stay bolt 3 having a body portion twisted as indicated at 4. The ends of this body portion are upset in order to form heads which are screw threaded as indicated at 5 and are arranged to engage screw threaded orifices in the plates 1 and 2. Each of these heads is provided with wrench seats 6, one of which is in the form of a socket, while the other is in the form of a head, and 7 indicates tell-tale holes which extend through the heads 5 into the body of the bolt.

In Fig. 2, I have shown a construction similar to that shown in Fig. 1, but one end

of the bolt is provided with a hemispherical head 12, which is adapted to engage a shoulder 10 in a threaded bushing 9, which is seated in the screw threaded orifice in the sheet 2. The inner end of the bushing 9 is flared as indicated at 11 in order to permit the bolt and head to vibrate within the bushing.

In Fig. 4, I have shown a construction similar to that shown in Fig. 2 with the exception that the body 13 is formed of tubular stock. In this construction the body of the bolt is also provided with a plurality of twists as indicated at 14. The heads of the bolt shown in Figs. 2 and 4 are provided with notches 16 for the reception of a tool for securing the bolts in position.

In Figs. 6, 7, 8 and 9, I have shown another modified form of bolt of rectangular cross section, and in which one portion of the body is at an angle to another portion thereof.

In Figs. 10 and 11, I have shown still another modified form in which the body is formed of stock of circular cross section, and in which I have forged rectangular portions throughout the length of the body as indicated at 20; the forged portions being at an angle with relation to each other. In this construction one end of the bolt is provided with a screw threaded head 5, which is adapted to engage a screw-threaded orifice in the sheet one, while the other end is screw-threaded; the outer diameter of these threads being of the same diameter as the diameter of the body of the bolt, as indicated at 19. 29 is a socket member having a screw threaded end 30, which is adapted to engage screw threads in an orifice in the sheet 2. This socket member is provided with a spherical recess which is arranged to receive the members 21, 22, 23 and 24, which form a sectional nut. 25 designates a nut having projections 26, which are adapted to loosely engage projections 27 on the cap 29.

This device is assembled as follows:—The members 21 to 24 are first inserted in the recess in the bushing 9; the nut 25 is then screwed on to the threaded end of the bolt a distance equal to the distance between the nut 25 and the members 21 to 24. The end of the bolt is then inserted into the members 21 to 24 and the bolt is screwed home into the nut 25 and the members 21 to 24. The

whole bolt is then inserted through the opening in plate 1 and the threads on the end of the member 29 are entered into the threads in the opening in the plate 2, and at the same time, the threads on the other head are entered in the threaded opening in the sheet 1. The whole device is then rotated to screw the bolt into position.

The advantages of my invention result from the provision of a stay bolt having a body which is of greater width than thickness, and in which one portion of the body is at an angle to another portion thereof to permit the bolt to yield to compensate for the shifting of one plate with relation to the other.

I claim:

1. A stay-bolt having a body portion of greater width than thickness, the parallel faces of the body portion at one point being parallel to the similar faces of the body portion at another point of the body and in-

termediate portions of the parallel faces being at an angle thereto, and securing means on the ends of said bolt, substantially as described. 25

2. A stay-bolt having a body portion of greater width than thickness, a securing head on each end of the body portion, said body portion being twisted at least 180 degrees about the longitudinal axis of the bolt, substantially as described. 30

3. A stay-bolt having threaded end portions and an intermediate portion of greater width than thickness, said portion being twisted helically through at least 180 degrees and the twist extending from the termination of the thread of one head to the beginning of the thread of the other head, substantially as described. 35

ETHAN I. DODDS.
